F. STROINSKI

OIL CUP CAP HOLDER

Filed Feb. 24, 1927

INVENTOR:
FRANK STROINSKI.
BY *Arthur O. Eberle*
ATTORNEY

UNITED STATES PATENT OFFICE.

FRANK STROINSKI, OF ST. LOUIS, MISSOURI.

OIL-CUP-CAP HOLDER.

Application filed February 24, 1927. Serial No. 170,656.

The object of my device is to make a holder for the cap for oil cups used in lubricating machinery. It is necessary to have a cap on the oil admission aperture of the 5 cup. In filling the cup the cap must be removed. When the cup is filled the cap must be attached. In a great many instances the oil cup is secured to a movable part of a machine. In the conventional 10 cap that is in threaded engagement with the cup, great losses have been incurred by the loss of the caps. These caps are usually made of brass and are internally threaded and are only bought at a considerably 15 high price even in large quantities. In the vibration of the cup the cap sometimes is loosened and falls off or may even be lodged on a movable belt or pulley and injure persons adjacent the machine to which the oil 20 cup is attached. In order to prevent the loss of these caps and thereby also to prevent accidents, my cap securing means is made.

My device can be made of two pieces of 25 wire properly bent, be made very inexpensively, is easily applied to any conventional cup and may be likewise easily removed from any conventional cup.

With these and other objects in view, my 30 invention has relation to certain novel features of construction and arrangement of parts as will be hereinafter more fully described, pointed out in the claim and illustrated in the drawing in which,

Fig. 1 is a front elevation of a conventional oil cup and cap with my device attached. The cap in its removed position is shown by dashed lines.

Fig. 2 is a perspective view of my device 40 and

Fig. 3 is a front elevation of the cap of the oil cup, showing the groove into which a portion of my device fits. Numeral 4 designates a conventional oil cup having the cap 45 5, which cap 5 is in threaded engagement with the top of the oil cup over the oil entrance aperture. Numeral 6 designates an annular groove in the cap 5. Numeral 7 designates the connection between the oil 50 cup and the machine to which it is attached.

My device consists of two pieces of wire 8 and 9, the portion 8 being used for securing to the connection 7 and the portion 9 being used for a connection with the cap 5. The piece 8 has its lower end bent as shown 55 at 10 into the form of a hook. The wire is sufficiently resilient that the hook 10 may be forced over the connection 7. The piece 8 extends laterally from the hook 10 and then at substantially right angles to the 60 plane of hook 10 for a distance equal to the height of the oil cup proper. The upper end is then bent slightly inwardly and has the eye 11 formed at its upper end. The piece 9 passes through the eye 11 and is supported 65 at its center. The material is likewise resilient. The prongs 12 are bent arcuately opposite each other so that when the piece 9 is slipped into the annular groove 6 of the cap 5, the cap is secured between the 70 arcuate extensions of the prongs 12. The portion of the piece 9 between the eye 11 and the prongs 12 is bent at an acute angle from the plane of the prongs 12. It will be 75 seen that when the cap 5 is unscrewed, and this unscrewing is made possible by the fact that the cap 5 can be turned between the prongs 12, it will assume the position shown in the dashed line in Fig. 1. Therefore, although the cap may be unscrewed, 80 it cannot be lost because it will be held between the prongs 12 of the piece 9.

What I claim and mean to secure by Letters Patent is:

A device of the character described, comprising two pieces of resilient wire, the end of one piece forming a hook, the other end of the same piece forming an eye, the two ends being joined by a portion of the piece extending laterally beyond and at right angles to the plane of the hook, the second piece extending through the eye of the first piece and having two prongs, each prong being bent outwardly in an arcuated manner opposite the other. 85 90 95

In testimony whereof I affix my signature.

FRANK STROINSKI.
